UNITED STATES PATENT OFFICE.

JAMES ANDERSON, OF BROOKLYN, NEW YORK.

WATER-PURIFYING APPARATUS.

SPECIFICATION forming part of Letters Patent No. 742,954, dated November 3, 1903.

Application filed March 6, 1903. Serial No. 146,457. (No model.)

To all whom it may concern:

Be it known that I, JAMES ANDERSON, a citizen of the United States, and a resident of Brooklyn, in the county of Kings and State of New York, have invented certain new and useful Improvements in Water-Purifying Apparatus, of which the following is a specification.

This invention relates to an apparatus for use in connection with exhaust-steam and a surface condenser for preventing the "pitting" of the condenser circulating-tubes and for purifying the water condensed from the exhaust-steam.

15 In the use of surface condensers the pitting of the circulating-tubes is due generally to the action of acids liberated from inferior oils entrained in the exhaust-steam and the deteriorating effect of the condensed water, 20 which cause the tubes to leak and the injection-water to enter and saturate the water of condensation with salt or other objectionable substance.

This invention consists, primarily, in inserting a chamber between the exhaust-steam passage and the condenser and providing a communicating auxiliary water-supply containing purifying ingredients, whereby the water of condensation is treated previous 30 to its contact with the circulating-tubes of the condenser. In addition to this other expedients may be added, such as oil separators or filters, to render the water of condensation practically free from impurities previous 35 to its return as feed-water to the steam-generator.

In the accompanying drawings, forming a part of this specification, Figures 1 and 2 represent a steam-motor, with an exhaust-chamber 8 and surface condenser 9 connected therewith, to which are respectively connected an auxiliary water-supply reservoir 1 and a solution-tank *a*, the condenser communicating with an air-pump *c*, that discharges 45 into a hot-well 10, which serves as an oil-separator. From the hot-well 10 a centrifugal pump 11 conveys the water of condensation to a filter-tank 12, from which, through the connection *d*, it is used to feed the steam-generator. The feed-water pipe connecting

55 with the filter-outlet *d* may be arranged to pass within the steam-exhaust chamber 8 in the form of a return-bend, as shown at *h*, for augmenting the temperature of the feed. The water-supply reservoir 1 is connected with the source of water-supply by means of the pipe 2, which extends to the height of the level in the reservoir. A valve 3 and float are attached to the end of the pipe, and the level of the water is thereby regulated. 60

a represents a chamber or tank in which a purifying material, such as caustic soda or other known purifying substance or compound, is placed. This chamber is connected with a pump 4, that delivers its contents 65 through the delivery-pipe 3 into the reservoir 1 and wherein it mixes with the water that is carried to the exhaust-steam chamber 8 through the pipe 5, a valve 7 being connected therewith to regulate the flow. The delivery-pipe 5 is provided at the end entering the chamber 8 with a rose-head 6, which sprays the solution into the exhaust-steam previous 70 to its entrance to the condenser 9.

From the condenser the condensed water 75 and air is drawn out by means of the usual air-pump *c*, which delivers into a hot-well 10. From this hot-well the entrained oil will float to the surface and may be readily removed by various known ways, or the hot-well may 80 be constructed like any of the known types of separators to serve the purpose. From the hot-well 10 a centrifugal pump 11 conveys the water, preferably from the lower part of the well, as shown, to a filtering-tank 12 and 85 from there through the pipe *d* it is conveyed for use to any desired place.

The means for separating and filtering shown are merely added to illustrate the complete method of operation of the invention 90 and are not separately claimed herein.

With my invention the use of compounds in the generators is avoided and the efficiency increased, as no solids remain in the feed-water, no loss is sustained by blowing off, nor 95 the formation of scale promoted.

What I claim, and desire to secure by Letters Patent, is—

1. The combination with a steam-exhaust and a surface condenser, of an interposed 100

chamber into which the steam is exhausted and a purifying feed-supply communicating with said chamber, as set forth.

2. The combination with a steam-exhaust, 5 of a chamber into which the steam is exhausted, a chemical-tank and a mixing-reservoir communicating with each other, the latter with said chamber for the purpose set forth.

Signed at New York, in the county of New York and State of New York, this 14th day 10 of February, A. D. 1903.

JAMES ANDERSON.
